United States Patent Office

Des. 188,556
Patented Aug. 9, 1960

188,556

HOLDER FOR PAPER PLATES

Ralph W. Theisen, Chicago, Ill., assignor to Hascot Corp., Chicago, Ill., a corporation of Illinois

Filed June 10, 1959, Ser. No. 56,303

Term of patent 7 years

(Cl. D44—10)

Fig. 1.

Fig. 2.

I claim:

The ornamental design for a holder for paper plates, substantially as shown and described.
